(57) **CLAIM**

The ornamental design for a projectile launcher as shown and described.

DESCRIPTION

FIG. 1 is a left/front/top perspective view of a projectile launcher according to my new design;

FIG. 2 is a left/front/bottom view thereof;

FIG. 3 is a right/rear/top view thereof;

FIG. 4 is a right/rear/bottom view thereof;

FIG. 5 is a top view thereof;

FIG. 6 is a bottom view thereof;

FIG. 7 is a left-side view thereof;

FIG. 8 is a right-side view thereof;

FIG. 9 is a front view thereof; and,

FIG. 10 is a rear view thereof.

The broken lines in the figures depict portions of the projectile launcher that form no part of the claimed design.

1 Claim, 10 Drawing Sheets
